US00D756572S

(12) **United States Design Patent**
Baker(10) **Patent No.:** **US D756,572 S**
(45) **Date of Patent:** **** May 17, 2016**(54) **WASTE COLLECTION DEVICE**

(71) Applicant: **Cheryl Davidson Baker**, Grand Junction, CO (US)

(72) Inventor: **Cheryl Davidson Baker**, Grand Junction, CO (US)

(**) Term: **14 Years**

(21) Appl. No.: **29/523,534**

(22) Filed: **Apr. 10, 2015**

(51) LOC (10) Cl. **30-99**

(52) U.S. Cl. **USPC D30/162**

(58) **Field of Classification Search**

Primary Examiner — Susan Moon Lee*(74) Attorney, Agent, or Firm* — Stanley J. Gradisar
Attorney at Law, LLC; Stanley J. Gradisar(57) **CLAIM**

The ornamental design for a waste collection device, as shown and described.

DESCRIPTION

FIG. 1 is a front perspective view of the waste collection device;

FIG. 2 is a left elevation view thereof;

FIG. 3 is a right elevation view thereof;

FIG. 4 is a front elevation view thereof;

FIG. 5 is a rear elevation view thereof;

FIG. 6 is a top plan view thereof; and,

FIG. 7 is a bottom plan view thereof.

Broken lines and unshaded portions contained within broken lines are not claimed.
